CLAIM

The ornamental design for a vacuum cleaner, as shown and
described.

DESCRIPTION

FIG. 1 is a perspective front, top, right view of a vacuum
cleaner showing the claimed design;

FIG. 2 is perspective front, top, left view of the vacuum
cleaner of FIG. 1;

FIG. 3 is a perspective front, bottom, right view of the
vacuum cleaner of FIG. 1;

FIG. 4 is a perspective front, bottom, left view of the vacuum
cleaner of FIG. 1;

FIG. 5 is a perspective rear, top, left view of the vacuum
cleaner of FIG. 1;

FIG. 6 is perspective rear, top, right view of the vacuum
cleaner of FIG. 1;

FIG. 7 is a perspective rear, bottom, right view of the
vacuum cleaner of FIG. 1;

FIG. 8 is a perspective rear, bottom, left view of the vacuum
cleaner of FIG. 1;

FIG. 9 is a front view of the vacuum cleaner of FIG. 1;

FIG. 10 is a rear view of the vacuum cleaner of FIG. 1;

FIG. 11 is a left view of the vacuum cleaner of FIG. 1;

FIG. 12 is a right view of the vacuum cleaner of FIG. 1;

FIG. 13 is a top view of the vacuum cleaner of FIG. 1; and,

FIG. 14 is a bottom view of the vacuum cleaner of FIG. 1.

(Continued)

The broken lines shown in the drawings are for the purpose of illustrating portion of the vacuum cleaner and form no part of the claimed design.
